STAND-OFF INSULATOR

Maurice G. Knoy, West Lafayette, Ind., assignor to
Rostone Corporation, Lafayette, Ind., a corporation of
Indiana

Filed Aug. 19, 1964, Ser. No. 81,405

Term of patent 14 years

(Cl. D26—10)

FIG. 1.

FIG. 2.

FIG. 3.

FIG. 4.

FIG. 5.

Fig. 6.

Fig. 7.

Fig. 8.

Fig. 9.

FIG. 10.

FIG. 18.

FIG. 11.

FIG. 19.

FIG. 12.

FIG. 13.

FIG. 14.

FIG. 15.

FIG. 16.

FIG. 17.

FIG. 1 is a front elevational view of a stand-off insulator, showing one form of my new design wherein the insulator includes a single rectangular pocket opening in each end portion and has a single attachment hole in each end, the rear being substantially a mirror image of the front;

FIG. 2 is a side elevational view of the form shown in FIG. 1, the opposite side being substantially a mirror image thereof;

FIG. 3 is a top plan view of the form shown in FIG. 1, the bottom having the same appearance;

FIG. 4 is a cross-sectional view of the form shown in FIG. 1 taken on the line 4—4 in FIG. 1;

FIG. 5 is a cross-sectional view of the form shown in FIG. 1, taken on the line 5—5 of FIG. 1;

FIG. 6 is a front elevational view of a stand-off insulator, showing another form of my new design wherein the insulator includes two transverse pocket openings in one end portion and three in the other end portion and has a plurality of attachment holes in both ends, the rear being substantially a mirror image of the front;

FIG. 7 is a side elevational view of the form shown in FIG. 6, the opposite side being substantially a mirror image thereof;

FIG. 8 is an end elevational view of the form shown in FIG. 6, taken from the top in FIG. 6, showing two attachment holes;

FIG. 9 is an end elevational view of the form shown in FIG. 6, taken from the bottom in FIG. 6, showing four attachment holes;

FIG. 10 is a cross-sectional view of the form shown in FIG. 6 taken on the line 10—10 in FIG. 6;

FIG. 11 is a cross-sectional view of the form shown in FIG. 6, taken on the line 11—11 of FIG. 6;

FIG. 12 is a cross-sectional view of the form shown in FIG. 6, taken on the line 12—12 in FIG. 6;

FIG. 13 is a front elevational view of a stand-off insulator, showing another form of my new design wherein the insulator has a plurality of attachment holes in both ends and includes two transverse pocket openings in one end portion and three in the other end portion, the side pocket openings being closed at one end, and wherein

the insulator includes a central cylindrical column, the rear being substantially a mirror image of the front;

FIG. 14 is a side elevational view of the form of FIG. 13, the opposite side being substantially a mirror image thereof;

FIG. 15 is an end elevational view of the form of FIG. 13, taken from the top in FIG. 13, showing two attachment holes;

FIG. 16 is an end elevational view of the form of FIG. 13, taken from the bottom in FIG. 13, showing four attachment holes;

FIG. 17 is a cross-sectional view of the form shown in FIG. 13, taken on the line 17—17 of FIG. 13;

FIG. 18 is a cross-sectional view of the form shown in FIG. 13, taken on the line 18—18 of FIG. 13;

FIG. 19 is a cross-sectional view of the form shown in FIG. 13, taken on the line 19—19 of FIG. 13.

The design is characterized by the generally spool shape of the insulator body, composed of three axially-spaced parallel round end- and mid-walls, chordal transverse walls adjoining the end walls and forming transverse rectangular pocket openings in the end portions of the body, and axially-extending strut walls between the end portions intersecting the mid wall, and presenting radially-disposed webs at rectangularly spaced positions about the body.

This application is a continuation-in-part of my co-pending application Serial No. D-76,758, filed September 27, 1963, now abandoned.

I claim:

The ornamental design for a stand-off insulator, as shown and described.
